UNITED STATES PATENT OFFICE.

WILLIAM E. WILSON, OF MASON CITY, IOWA, AND HENRY G. LYKKEN, OF MINNEAPOLIS, MINNESOTA.

TILE AND TILE ARCH.

Application filed April 14, 1921. Serial No. 461,469.

This invention relates primarily to tiles and tile arches employed in the construction of tunnel kilns, but is not limited in its application to such use. Among the objects 5 of our invention are: to provide a new and improved tile for the construction of tile arches; to provide a new construction of tile arch; to provide improved means for permitting expansion and contraction of the 10 tiles in tile arches, without placing strain on the tiles; and such further objects, advantages and capabilities as will later more fully appear.

Our invention further resides in the combination, construction and arrangement of parts illustrated in the accompanying drawings, and while we have shown therein preferred embodiments we desire the same to be understood as illustrative only and not as 20 limiting our invention.

In the accompanying drawings, Fig. 1 is an end view of one form of tile embodying our present invention; Figs. 2, 3 and 4 are cross sections of tile arches constructed in 25 accordance with our present invention; Fig. 5 is an isometric cross section of a tile arch supported by structural steel; Fig. 6 is an isometric view of a tile such as that shown in Fig. 1, and Fig. 7 is a fragmentary section showing a modified form of tile having spacing ridges, lugs, or the like, on the projecting flanges, to cause spacing of the tiles and reduce friction tending to prevent 30 the tiles from sliding with respect to one another when heated.

Referring more in detail to the annexed drawings, numerals 1, 2, 3 and 4 designate four different tiles embraced in our invention, those shown in Figs. 1, 6 and 7 being 40 hollow, while those shown in Figs. 2, 3, 4 and 5 are solid. It will be obvious from Figs. 1, 6 and 7 that the hollow tiles may be formed with longitudinal apertures of any desired shape, such as circular, square 45 or oblong in cross section, but, as shown in these figures, it is preferable that there be a central aperture 5, extending substantially across the tiles. Between the ends of this aperture 5 and the side walls of the tile are slits 6 which weaken these walls of the tile so that it can be readily broken in two by 50 being suitably struck. This will result in the formation of half tiles, which may be used in the same manner as tiles 3 in Figures 2 to 5. The tiles 4 are formed in sub-

stantially the same manner as the tiles 1, but are provided at certain edges with ridges, lugs, or the like, 7. These result in the production of air spaces between the tiles when they are built into a construction as 60 shown in Fig. 7. These projections also result in the decrease in the amount of friction between engaging spaces and therefore make it easier for them to slide on each other when the tile arch is heated during use. 65 With the constructions shown in Figs. 1 and 2, this result is in part accomplished in a different manner, that is, by inserting between the tiles, at the points marked 8, strips of paper or the like. When the kiln is 70 heated these strips of paper will burn out and leave spaces between the tiles to accommodate the expansion due to heating of the tiles.

The various forms of construction of the 75 tile arch will next be described. Fig. 2 shows the construction of a tile arch comprising whole tiles 2 and half tiles 3 supported by concrete 9 having embedded therein reinforcing rods 10. It will be obvious 80 that when this construction has been erected and has become thoroughly set, if a fire is started and the kiln is heated to a high temperature, the paper or the like at 8 will be 85 burned out and will leave a slight space at these points for the necessary relative movement caused by the expansion and contraction of the tiles when heating up and cooling down.

The construction of Fig. 3 is similar to 90 that of Fig. 2 but has supporting I-beams, portions of which are embedded in the concrete 9. Connecting the I-beams 11 are tie-rods 12 which are embedded in the concrete 9 and hold the I-beams in position. This 95 figure also shows the use of an extra layer of tiles 2 to increase the thickness of the kiln structure.

In Fig. 4 a plurality of reinforced concrete girders take the place of the I-beams 100 11 shown in Fig. 3 and these are stayed by cross beams 14 which take the places of the tie-rods 12 of Fig. 3. It will be noticed that in this figure the thickness of the tiling is 105 midway between the thicknesses shown in Figs. 2 and 3. The tiles 2 and 3, the paper strips in spaces 8, the concrete 9 and the reinforcing rods 10 are the same in this figure as in the preceding figures.

In Fig. 5, I-beams 11 support channel irons 110

14, which are tied together and held braced with respect to each other by means of bolts 15 and cross pieces 16. On the lower flanges 17 of these channel irons 14 rest flanges of the tiles 2, which in turn support the next lower layer of tiles 2, as is obvious.

Most of the forms disclosed herein are adapted, not only for arch construction, but, also for floor construction, being well insulated because the concrete nowhere extends clear through and by reason of the air spaces between the tiles. Furthermore these constructions produce superior results in the way of sound insulation, both for floors and 13 ceilings, due primarily to the fact that the structure is not a solid concrete.

It is of course understood that the specific description of structure and method set forth above may be departed from without departing from the spirit of our invention as set forth in this specification and the appended claims.

Having now described our invention, we claim:

- 25 1. A tile arch or floor comprising a flanged super-structure having pairs of laterally directed, oppositely extending spaced flanges, spaced tiles having oppositely extending flanges resting on the first named flanges so as to support the tiles, said tiles having other laterally directed flanges, and other tiles having laterally directed flanges resting on the second named flanges to support said last named tiles.
- 25 2. In a tile structure, a reinforced concrete super-structure having downwardly extending spaced ribs provided with laterally extending flanges, spaced, laterally flanged tiles in the spaces between the ribs, some of the flanges of the tiles resting on the flanges of the ribs to support the tiles therefrom, said tiles having other laterally directed flanges, and other tiles provided with laterally projecting flanges resting on the second named flanges of the first named tiles

so that the second named tiles will be supported by the first named tiles.

3. In a tile structure, a plurality of I-beams, flanged means supported by said I-beams, the flanges of said means extending laterally toward each other and being spaced apart to act as supporting means for laterally flanged tiles, laterally flanged tiles arranged between the flanges of the supporting means and having their flanges resting on the flanges of the supporting means, and other tiles between the first named tiles and suspended thereby in a lower plane than the previously mentioned tiles.

4. In a tile, a body portion and flanges extending laterally from opposite faces, said flanges being substantially parallel, said flanges having projections thereon so that when the flanges of one tile rest on the flanges of adjacent tiles there will be between the adjacent flanges, substantial spaces.

5. A tile arch or floor comprising a flanged super-structure having pairs of laterally directed, oppositely extending spaced flanges, spaced tiles having oppositely extending flanges resting on the first named flanges so as to support the tiles, said tiles having other laterally directed flanges, and other tiles having laterally directed flanges resting on the second named flanges to support said last named tiles, said flanges having on their co-operating faces projections adapted to produce between said faces substantial air spaces.

6. A tile arch or floor comprising spaced tiles having oppositely extending flanges and other tiles having laterally directed flanges resting on the first named flanges to support said last named tiles in a lower plane than the first named tiles.

In witness whereof, we hereto subscribe our names to this specification.

WM. E. WILSON.
HENRY G. LYKKEN.
